TILTABLE PACKING TABLE

Frederick F. Sutherland, Cumberland, Md., assignor to Celanese Corporation of America, a corporation of Delaware

Application February 6, 1946, Serial No. 645,844

8 Claims. (Cl. 226—129)

1

This invention relates to a conveyor system for handling objects such as packing cases, and relates more particularly to an improved conveyor system provided with a movable, tiltable section whereby packing cases riding along the conveyor system may be tilted out of line to facilitate the loading thereof.

An object of this invention is to provide a tilting section in a packing case conveyor system adapted to shift a packing case resting thereon out of the main conveyor line and simultaneously to tilt the case and to render the bottom-most section of the case on the tilted section of the conveyor system more easily accessible for proper packing thereof.

Another object of this invention is the provision of tilting means in a section of a conveyor system adapted to tilt an object, such as a packing case, riding thereon to the desired angle and to lock said case in tilted position automatically in a single operation.

Other objects of this invention will appear from the following detailed description and the accompanying drawings.

In the drawings,

Fig. 1 is a side elevational view of the novel tilting section of my invention having a packing case thereon, showing mechanism for drawing the section out of line and simultaneously tilting it, and

Fig. 2 is a front elevational view of a conveyor line having the novel tilting section of my invention in combination therewith showing the handle whereby the tilting section and the case thereon may be drawn from the main conveyor line and placed in tilted position.

Like reference numerals indicate like parts throughout both views of the drawings.

Referring now to the drawings, and more particularly to Fig. 2, the main packing case conveyor line employed in connection with my novel tilting section comprises, in its several parts, stationary sections 3, only portions of which are shown, together with a short stationary section 4 intermediate thereof in the gap formed by the removal of the tilting section. Thus, the novel tilting section of my invention, generally indicated by reference numeral 5, is so positioned that the framework thereof straddles stationary section 4. The construction and operation of said tilting conveyor section is hereinafter described. Stationary sections 3 and 4 are provided with a plurality of cylindrical rollers 6, which rollers are rotatably mounted in horizontal supporting members 7 and 8, respectively. The sev-

2

eral supporting members 7 are set on posts 9 anchored to the flooring by suitable means (not shown). Supporting member 8 of the central or stationary section 4 is set on posts 10 fixed to the flooring by bolts 11. The stationary sections 3 and 4 of the conveyor system are capable of carrying any heavy object such as a packing case, for example, the latter being indicated by reference numeral 12. Packing case 12 may be moved along the conveyor line independent of tilting conveyor section 5, it being large enough to bridge the gap formed when the tilting section is removed from the conveyor system.

The tilting conveyor section 5 of my invention comprises a framework consisting, in its several parts, of a pair of horizontal rectangular structural members 13 having a plurality of cylindrical rollers 14 rotatably mounted therein, and a U-shaped channel member 15 set beneath and attached to members 13 to provide additional rigidity and strength. Channel member 15 is connected to rectangular members 13 through the brackets 16 mounted on channel 15 by means of bolts 17. Brackets 16 are pivotally linked to a second pair of brackets 18 through pins 19, brackets 18 being fixed to members 13 by means of bolts 20.

The entire tilting conveyor section 5 rides out of the main conveyor line consisting of stationary sections 3 and 4, on a plurality of casters 21. Casters 21 are attached to the lower side of channel 15 in any suitable manner and are provided with grooved wheels 22 set on tracks 23 which are anchored to the flooring by bolts 24.

To effect the desired tilting action in conveyor section 5, when the latter is drawn out of the main conveyor line, there is provided an inclined stationary trackway which consists of a pair of guide rails 25 mounted on posts 26 and 27. The latter are anchored to the flooring by bolts 28 and 29 which pass through angle irons 30 and 31, respectively. Posts 26 and 27 are welded to said angle irons and the latter serve to give the posts greater strength and rigidity. Guide rails 25 which comprise the inclined trackway each contains a roller 32 rotatably mounted on a short shaft 33. Shafts 33 are attached to dependent legs 34 welded to angle irons 35 which, in turn, are welded to the lower side of rectangular members 13.

In order to draw the conveyor section 5 out of the main conveyor line and to effect the tilting of packing case 12, when the latter is in position on said tilting conveyor section 5, as shown in Fig. 2, the operator grasps the handle 36 at-

tached to said tilting conveyor section and draws it towards himself. This action causes the entire conveyor section 5 to move out of the main conveyor line with wheels 22 rolling forward on tracks 23. At the same time, wheels 32 ride upward on inclined rails 25 thus causing the entire conveyor section 5 to tilt toward the operator. The entire section moves forward and continues to tilt until wheels 32 strike stops 36. When wheels 32 come in contact with stops 36, case 12 is in the position 12' shown in dot-dash lines in Fig. 1 and comes to rest on a brake or stop member 37 pivoted on post 37'. Stop member 37 and post 37' are not shown in Fig. 2 for the sake of clarity. The upper surface of stop member 37 is covered with rubber to prevent packing case 12 from moving, laterally of the tilting section, on rollers 14. As the conveyor section 5 is tilted as far as it will go, it is simultaneously locked into tilted position by the action of a trigger 38 which hooks under a catch 39. In position 12' the packing case may be packed efficiently since the bottom thereof is within easy reach.

After case 12 has been packed and is to be returned to the main conveyor line, the operator forces lever 40 toward handle 36 which causes rod 41 to move upward. This action draws trigger 38 from catch 39 since the upward movement of rod 41 causes trigger 38 to pivot in bracket 42 in which said trigger 38 is mounted, and to be thus released. The downward pull exerted by the weight of loaded case 12 together with a slight push on handle 36 by the operator after trigger 38 is released, rolls the tilting conveyor section 5 back into the main conveyor line. When both the stationary and tilting conveyor sections are in normal running position, rollers 14 are lined up with rollers 6 of the main conveyor. While rollers 14 may be on the same level as rollers 6, as shown in Fig. 2, rollers 14 are preferably set slightly higher than rollers 6 so that the loaded packing case 12 may again be started along the main conveyor line with as little effort as possible.

It is to be understood that the foregoing detailed description is given merely by way of illustration and that many variations may be made therein without departing from the spirit of my invention.

Having described my invention what I desire to secure by Letters Patent is:

1. A conveyor system comprising a stationary framework having a plurality of rollers mounted therein, a laterally separable framework normally in alignment with said stationary framework and also having rotatably mounted rollers therein, a truck on which said laterally separable framework is mounted, a trackway adjacent to said framework and a member on said separable framework operatively connected to said trackway, the construction and arrangement being such that, upon lateral movement of said truck to move said separable framework out of alignment with said stationary framework, said member moves in said trackway and causes said separable framework to be tilted.

2. A conveyor system comprising a stationary framework having a plurality of rollers mounted therein, a laterally separable framework normally in alignment with said stationary framework and also having rotatably mounted rollers therein, a truck on which said laterally separable framework is mounted, an inclined trackway adjacent

5 to said framework and a member on said separable framework operatively connected to said trackway, the construction and arrangement being such that, upon lateral movement of said truck to move said separable framework out of alignment with said stationary framework, said member moves in said trackway and causes said separable framework to be tilted.

3. A conveyor system comprising a stationary framework having a plurality of rollers mounted therein, a laterally separable framework normally in alignment with said stationary framework and also having rotatably mounted rollers therein, a truck on which said laterally separable framework is mounted, a stationary, inclined trackway adjacent to said framework and a member on said separable framework operatively connected to said trackway, the construction and arrangement being such that, upon lateral movement of said truck to move said separable framework out of alignment with said stationary framework, said member moves in said trackway and causes said separable framework to be tilted.

4. A conveyor system comprising a stationary framework having a plurality of rollers mounted therein, a laterally separable framework normally in alignment with said stationary framework and also having rotatably mounted rollers therein, a truck on which said laterally separable framework is mounted, a stationary, inclined trackway adjacent to said framework, a leg on said separable framework and a roller journaled on said leg for movement in said trackway, the construction and arrangement being such that, upon lateral movement of said truck to move said separable framework out of alignment with said stationary framework, said roller moves in said trackway and with said leg causes said separable framework to be tilted.

5. A conveyor system comprising a stationary framework having a plurality of rollers mounted therein, a laterally separable framework normally in alignment with said stationary framework and also having rotatably mounted rollers therein, a truck on which said laterally separable framework is mounted, a plurality of stationary, inclined trackways adjacent to said framework, a plurality of legs on said separable framework and a roller journaled on each of said legs for movement in said trackway, the construction and arrangement being such that, upon lateral movement of said truck to move said separable framework out of alignment with said stationary framework, said rollers move in said trackways and with said legs cause said separable framework to be tilted.

6. A conveyor system comprising a stationary framework having a plurality of rollers mounted therein, a separable framework normally in alignment with said stationary framework and also having rotatably mounted rollers therein, a truck on which said separable framework is mounted, wheels on said truck, a plurality of tracks for guiding said wheels, a plurality of stationary, inclined trackways adjacent to said framework, a plurality of legs on said separable framework and a roller journaled on each of said legs for movement in said trackway, the construction and arrangement being such that, upon lateral movement of said truck to move said separable framework out of alignment with said stationary framework, said rollers move in said trackways and with legs cause said separable framework to be tilted.

7. A conveyor system comprising a stationary framework having a plurality of rollers mounted therein, a separable framework normally in alignment with said stationary framework and also having rotatably mounted rollers therein, a truck on which said separable framework is mounted, wheels on said truck, a plurality of tracks for guiding said wheels, a plurality of stationary, inclined trackways adjacent to said framework, a plurality of legs on said separable framework, a roller journaled on each of said legs for movement in said trackway, the construction and arrangement being such that, upon lateral movement of said truck to move said separable framework out of alignment with said stationary framework, said rollers move in said trackways and with said legs cause said separable framework to be tilted, and means attached to said separable framework for locking the same in tilted position.

8. A conveyor system comprising a stationary framework having a plurality of rollers mounted therein, a separable framework normally in alignment with said stationary framework and also having rotatably mounted rollers therein, a truck on which said separable framework is mounted, wheels on said truck, a plurality of

tracks for guiding said wheels, a plurality of stationary, inclined trackways adjacent to said framework, a plurality of legs on said separable framework, a roller journaled on each of said legs for movement in said trackway, the construction and arrangement being such that, upon lateral movement of said truck to move said separable framework out of alignment with said stationary framework, said rollers move in said trackways and with said legs cause said separable framework to be tilted, and means, comprising a catch and a releaseable trigger attached to said separable framework, for locking the same in tilted position.

Certificate of Correction

Patent No. 2,522,588

September 19, 1950

FREDERICK F. SUTHERLAND

It is hereby certified that error appears in the printed specification of the above numbered patent requiring correction as follows:

Column 4, line 74, before the word "legs" insert *said*;
and that the said Letters Patent should be read as corrected above, so that the same may conform to the record of the case in the Patent Office.

Signed and sealed this 5th day of December, A. D. 1950.
